UNITED STATES PATENT OFFICE.

WILLIAM F. ZIMMERMANN, OF MAPLEWOOD, NEW JERSEY.

SHAPING MACHINE WITH VARIABLE-POWER TRAVERSE.

Application filed March 13, 1926. Serial No. 94,622.

This invention relates to shapers of the power quick-traverse type proposed by my two Patents 1,615,185 and 1,665,389, issued on my pending applications (Nos. 87,068 and 94,451 filed respectively on February 9, 1926, and March 13, 1926) and it undertakes to carry forward and improve upon the same.

The aforesaid initial embodiments of the power quick-traverse, possess the striking advantage that the tool strokes may be varied to any extent without affecting the rate of traverse, but to do this the main-line transmission was shown as substantially coextensive with the main body-casting. I have now contrived, by adopting a dependence between the tool strokes and the rate of traverse, to extend the main line transmission to the cross rail and, at that locality, to mount the two branch-line transmissions for the feed and the power quick-traverse; thereby materially reducing the number of elements and better adapting the machine for the more intensive sort of heavy-duty labor involved in severe production manufacturing.

In the aforesaid embodiments, the magnitude of feed was adjusted at the body-casting and its direction at the cross-rail so that the controls were scattered. The present arrangements make it possible to centralize the controls for the power quick-traverse, as well as of the feed, and thereby relieve the attendant from the loss of time due to the original inconvenience of dispersed controls.

By the present construction, it has become possible to bring within the immediate reach of the user the control for the rapid traverse and also all of the controls for the feed which were located near the bull-gear; all of these controls being now located at the cross-rail and being (a) for starting either the rapid traverse or the feed, (b) for changing the direction of either and (c) for varying the magnitude of the feed. Furthermore, all of the hand-grasps for the various controls have not only been relocated and centralized where most accessible to the user, but all of the hand-grasps are stationary and devoid of all rhythmic movement; thereby enabling the attendant to make his adjustments with ease and accuracy.

Also, the main-line transmission is so extended to the cross-rail, that the synchronism between the feed and the ram is preserved for all speed-adjustments of the ram; said extension including a single unidirectional shaft which rotates at rates determined by

the change-gears for the ram and conveys motion which, at the rail, is converted into intermittent motion for the feed or into continuous motion for the rapid traverse. In this instance, the rate of the traverse is proportional to the frequency of oscillations of the ram, but with the result that the structure has been simplified and the attendant has been spared all avoidable movements. A wide variation in the rate of quick-traverse would be intolerable but, for special purpose shapers of the manufacturing type, the range would be narrow and would include an average absolute rate for which the machine would be designed to run; the factors being determined by the limited scope but nevertheless large quantities of work to be machined in the quantity production.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Figure 1 is an elevational view of a shaping machine having feeding mechanism constructed in accordance with my invention. Fig. 2 is a sectional view along the line 2—2 of Fig. 1. Fig. 3 is a sectional view along the line 3—3 of Fig. 2. Fig. 4 is a plan view of feeding mechanism mounted on the end of the shaper rail. Fig. 5 is a sectional view along the line 5—5 of Fig. 4. Fig. 6 is a sectional view along the line 6—6 of Fig. 4. Fig. 7 is a sectional view along the line 7—7 of Fig. 1.

Referring to the accompanying drawings, a shaping machine is illustrated comprising a main frame 1 having a reciprocating ram 2 mounted thereon. The ram 2 carries a tool-head 3 having a suitable cutting tool 4 mounted therein. A rocker-arm 5, which is oscillated in a conventional manner by a crank gear wheel 6, serves to effect reciprocatory movement of the ram 2. The rocker arm 5 is clamped to the ram 2 by means of a lever 7 and a shaft 8, which operates a screw shaft, not illustrated, is provided for adjusting the ram with respect to the rocker

arm. A cross rail 9 is movable vertically on the main frame 1 of the machine and carries a work carrying table 10. The work carrying table 10 is fed and traversed along the cross rail 9 by means of a feed screw 11 in a manner to be hereinafter set forth.

The crank gear wheel 6 has a bearing in a hub 12 projecting from the main frame 1 of the machine as shown in Fig. 7 of the drawings. A plate 13, which is secured to the gear wheel 6 by means of bolts 14, serves to prevent axial or longitudinal movement of the gear wheel in the frame. An adjusting shaft 15, which controls the connection of the crank gear wheel 6 to the rocker arm 5 projects through the plate 13 and the crank gear wheel 6 as shown in Fig. 7 of the drawings. The shaft 15 is provided with a squared end 16 for operating it in the usual manner. The mechanism operated by the shaft 16 is old and well-known and accordingly a description thereof is deemed unnecessary. A bevel gear wheel 17, which is rotatable with respect to the shaft 15, is secured to the plate 13 by means of bolts 18, one only of which is illustrated on the drawings. The bevel gear wheel 17 meshes with a bevel gear wheel 19, which is connected to a connecting feed rod in the form of a universal shaft. The rod 20 extends to the cross rail 9 of the machine and is continuously rotated in a uniform direction by the crank gear wheel 6 directly in accordance with the movement of the ram 2. The connecting rod 20 is pivotally joined to a shaft 21 on the cross rail 9.

The shaft 21 is journaled in a housing 22 which is directly secured to the cross rail 9. On the end of the shaft 21 is fixedly mounted a crank lever 23. The crank lever 23 is connected to a crank arm 24 by means of a pin 25. The crank arm 24 is secured to an oscillating lever 26 by means of a pin 27, as best shown in Fig. 2 of the drawings. The oscillating lever 26 is journaled in a wall 28 of the housing 22 and serves as a support for one end of a feed shaft 29. Inasmuch as the shaft 21 is continuously rotated by means of the connecting rod 20 it is apparent the oscillating lever 26 is continuously moved through a fixed arc by means of the crank arm 24.

An arm 30, which projects from the oscillating lever 26, engages a surface 31 on a pawl lever 32. The pawl lever 32 is rotatably mounted on the feed shaft 29 and is oscillated through various arcs by the oscillating lever 26 to effect feeding movements of the work carrying table 10. A ring 33, having worm teeth 34 formed thereon, is secured to the pawl lever 32 and serves to adjust the rotative position of the pawl lever 32 on the feed shaft 29. The worm teeth 34 engage a worm 35 which is formed on a worm shaft 36. The worm shaft 36 is ro-

tatably mounted in the housing 22 as best shown in Fig. 6 of the drawings. A spring member 37, which extends into an orifice 38 formed in the shaft 36, exerts a force tending to hold the shaft 36 in engagement with an adjustment shaft 39. One end of the spring member 37 engages the worm shaft 36 and the opposite end engages a plug 44. The plug 44 is adjusted in the housing 32 to vary the tension of the spring member. The shaft 39 is provided with a rectangular portion 40 which fits in a slot formed in the upper end of the worm shaft 36. The adjusting shaft 39 is rotatably mounted in a plate 41, which is secured to the housing 22. A hand grasp 42 is secured to the shaft 39 on one side of the plate 41 and a gear wheel 43 is secured to the shaft 39 on the opposite side of the plate 41. The worm shaft 36 is rotated in accordance with the movement of the hand grasp 42 but is free to move longitudinally or axially with respect to the shaft 39.

The gear wheel 43, which is fixedly mounted on the shaft 39, meshes with a gear wheel 45 which is connected to a graduated dial 46. The dial 46 is mounted on one side of the plate 41 whereas the gear wheel 45 is mounted on the opposite side of the plate. A spring pressed ball 47 engages suitable detents formed in the upper surface of the gear wheel 45 for holding the dial 46 and the hand grasp 42 in any operative position. The graduations on the dial 46 are so formed as to indicate the exact rate of feeding that is being effected by the work table 10.

In the above described mechanism the hand grasp 42 is operated to vary the rotative position of the pawl lever 32 on the feed shaft 29. The position of the pawl lever 32 on the feed shaft 29 determines the arc through which the pawl lever is operated. Movement of the oscillating lever 26 in one direction causes the arm 30 to engage the pawl lever 32 and move it through an arc in opposition to the spring member 37. When the movement of the oscillating lever 26 is reversed the spring member 37 moves the pawl lever with the oscillating lever until the pawl lever is in its initial position. The initial position of the pawl lever is, as before set forth, adjusted by means of the worm member 35, which is operated by means of the hand grasp 42.

A pawl member 49 is pivotally mounted on the pawl lever 32 by means of a pin 50. The pawl member 49 engages the teeth of a ratchet wheel 51 which is rotatably mounted on the feed shaft 29. The teeth on the ratchet wheel 49 are so formed as to effect movement with the pawl member 49 only when the pawl member is being moved in one direction. A clutch member 52 is splined to a sleeve member 53 adjacent to the ratchet wheel 51. The clutch member 52 is

provided with clutch teeth 54 which are adapted to be moved in engagement with similar clutch teeth 55 on the side of the ratchet wheel 51. A yoke member 56, which engages a groove formed on the clutch member 52, is operated by a lever 57^a for moving the clutch member into driving engagement with the ratchet wheel 51. The sleeve member 53 is rotatably mounted on the feed shaft 29 and projects through a gear wheel 57. The gear wheel 57 is journaled in a wall of the housing 22, as shown in Fig. 3 of the drawings, and meshes with a gear wheel 58. The gear wheel 58 is fixedly mounted on the shaft 21. The gear wheel 57 has clutch teeth formed on the side thereof which are adapted to engage similar clutch teeth formed on the clutch member 52. A plate 59 is splined to the sleeve 53 and is held in engagement with a shoulder 60 on the sleeve member by means of spring members 61. The spring members 61 project into orifices formed in a collar 62, which is also splined to the sleeve 53. A washer 63, of friction material and preferably of leather, is positioned between the collar 62 and a disc 64. The disc 64 is splined to the feed shaft 29 and engages a nut 65 on the shaft 29. The plate 59 and the disc 64 with the parts included between them serve as a friction drive between the feed shaft 29 and the feeding and traversing mechanism operated by the connecting rod 20. The friction clutch comprising the plate 59 and the disc 64 is adjusted by means of the nut 65 on the end of the shaft 29.

The lever 57^a, which controls the clutch member 52, determines whether a feeding or a traversing movement would be effected by the work carrying table 10. When the clutch member 52 is moved towards the left, as viewed in Fig. 3 of the drawings, the ratchet wheel 51 is connected to the feed shaft 29 through the sleeve member 53 and the friction clutch comprising the plate 59 and the disc 64. The ratchet wheel 51 is intermittently moved in a uniform direction an amount determined in accordance with the arc of oscillation of the pawl lever 32. The arc of oscillation of the pawl lever 32 is controlled by means of the hand grasp 42. When the clutch member 52 is moved toward the right, as viewed in Fig. 3 of the drawings, the gear wheel 57 is connected to the feed shaft 29 through the sleeve 53 and the friction clutch comprising the plate 59 and the disc 64. The gear wheel 57 is continuously rotated by means of the gear wheel 58 which is continuously rotated by means of the connecting rod 20.

A bevel gear wheel 66, which is mounted on one end of the feed shaft 29, meshes with two bevel gear wheels 67 and 68. The two bevel gear wheels 67 and 68 are rotatably supported on the feed screw 11 by means of two bushings 70 and 71. A clutch member 72, which is splined to the feed screw 11, is positioned between the two bevel gear wheels 67 and 68, as shown in Fig. 2 of the drawings. The bevel gear wheels 67 and 68 are provided with clutch teeth on the sides thereof which are adapted to be engaged by similar clutch teeth on the clutch member 72. Thus, movement of the clutch member 72 in one direction serves to connect the bevel gear wheel 67 to the feed screw and movement of the clutch member in an opposite direction serves to connect the bevel gear wheels 68 to the feed screw 11. Such clutch member 72 serves to control the direction of rotation of the feed screw 11 and accordingly to control the direction of the feeding and traversing movements which are effected by the table 10. A rod 75, which has a bearing in the housing 22, carries an eccentric pin 76. The pin 76 extends into a groove 77 in the clutch member 72. Thus, the clutch member 72 is moved along the feed screw 11 in accordance with the rotative movement of the rod 75. The rod 75 is controlled by means of a hand grasp 78. A set screw 79, which is secured in the housing 22, projects into a groove 80 in the rod 75 and serves to prevent axial movement of the rod in the housing 22. A spring pressed ball 81 engages detents formed in the rod 75, as shown in Fig. 5 of the drawings, for exerting a force tending to hold the clutch member 72 in neutral or in either of its operative positions.

In the feed mechanism constructed as above set forth continuous rotary movement is supplied from the crank gear mechanism through the connecting rod 20, for operating the work carrying table 10. The work carrying table 10 may be intermittently fed in accordance with the movement of the ram 2 or may be continuously traversed in either direction. Attention is further called to the fact that the direction of the feeding movements and the direction of the traverse movements are controlled at a point on the cross rail. Moreover means is provided on the cross rail for determining the rate of feeding movements and also for selectively determining whether a feeding or a traverse movement will be effected. The direction of the feeding or traversing movement is controlled by the hand grasp 78, which operates the clutch member 72, in the manner heretofore described. The clutch member 72 controls the direction of rotation of the feed screw 11. The rate of the feeding movements is controlled by the hand grasp 42 which operates the worm 35. The worm 35 varies the rotative position of the pawl lever 32 to vary its arc of oscillation. The rate at which feeding is being effected

is indicated by the graduated dial 46 which is moved in accordance with the movement of the hand grasp 42. The lever 57^a controls the clutch member 52 for determining whether intermediate feeding members or continuous traverse movement of the work carrying table 10 will be effected.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be comprehended within the meaning and range of equivalency of the following claims.

Having thus revealed this invention, I claim as new and desire to secure the following combinations and elements, or equivalents thereof, by Letters Patent of the

25 United States:—

1. A shaper combining a cross-rail; a table; a propelling-transmission therefor; a feed transmission adapted to impart intermittent motion to said table-transmission in a given direction; a feed rate-adjuster located at the cross-rail; a quick-traverse transmission adapted to impart continuous motion to said table transmission; and a shift-mechanism arranged to cause either said quick-traverse transmission or said feed transmission to drive said table.

2. A shaper combining a cross rail; a table; a power-driven element; a transmission from said element to said table including two interchangeably available branch-lines, the one adapted to convey slow intermittent feed motion and the other in the same direction to convey fast continuous motion; a shift-mechanism; an independent motion-reverser for simultaneously reversing the directional effects on the table of both of said branch-lines; and a feed rate-adjuster located at the cross-rail.

3. A shaper combining a cross rail; a table; a main body-casting; a single unidirectional transmission extending from the body-casting to the cross rail; a feed transmission including a motion-converter at the cross-rail adapted to impart intermittent motion to said table in a given direction; a quick-traverse transmission adapted to impart continuous motion to said table; and a shift-mechanism located at the cross-rail and arranged so to connect said quick-traverse transmission that it will drive said table.

4. A shaper combining a table; a cross-rail; a main body-casting; a power-driven element; a unidirectional transmission shaft leading from said element to two inter-

changeably available branch-lines, the one including a motion converter at the cross-rail adapted to impart slow intermittent motion, and the other conveying fast continuous motion; a shift-mechanism for said transmissions and an independent motion-reverser located at the cross-rail for simultaneously reversing the directional effects on the table of both of said branch-lines.

5. A shaper combining a body-casting; a ram; a unidirectional bull-gear; a cross-rail; a table; a transmission-system leading to said table and comprising a unidirectional common shaft driven synchronously with said bull-gear and leading from the side of said body-casting adjacent said bull-gear to said cross-rail; an intermittent-motion transmission comprising a feed-stroke regulator; a continuous motion transmission; a clutch for causing said common shaft to drive either of said two transmissions synchronously with said bull-gear; and a single motion-reverser for simultaneously reversing the directional effects on the table of both of said transmissions.

6. A shaper combining a body-casting; a ram; a unidirectional bull-gear; a cross-rail; a table; a transmission-system leading to said table; a bull-gear transmission; an intermittent-motion transmission driven synchronously with said bull-gear and comprising a feed-stroke regulator; a fast-motion transmission deriving motion from said bull-gear transmission and driven synchronously with said bull-gear; a clutch for causing either of said two transmissions to convey motion to said first-mentioned transmission system; and a single motion-reverser for simultaneously reversing the directional effects on the table of both of said transmissions.

7. A shaper combining a body-casting; a ram; a unidirectional bull-gear; a cross-rail; a common shaft therein; a table; a transmission-system leading to said table and comprising a single unidirectional shaft from the side of said body-casting adjacent said bull-gear to said cross-rail; an intermittent-motion transmission driven synchronously with said bull-gear and comprising a feed-stroke regulator located adjacent said cross-rail; a continuous fast-motion transmission; a clutch adjacent said cross-rail for connecting either of said two transmissions with said common shaft; and a single motion-reverser located at the cross-rail for simultaneously reversing the directional effects on the table of both of said transmissions.

8. A shaper combining a body-casting; a ram; a unidirectional bull-gear; a cross-rail; a table; a transmission-system leading to said table; a bull-gear transmission; a transmission driven synchronously with said bull-gear and comprising a motion-converter at

the cross-rail for producing intermittent feed motion; fast-motion transmission; a clutch for causing either of said two transmissions to convey motion to said first-mentioned transmission system; and a manual control for said clutch.

9. A shaper combining a body-casting; a ram; a unidirectional bull-gear; a cross-rail; a table; a transmission-system leading to said table; a bull-gear transmission; a transmission driven synchronously with said bull-gear and comprising a motion-converter located at the cross-rail for producing intermittent motion; fast-motion transmission; a clutch for causing either of said two transmissions to convey motion to said first-mentioned transmission system; and a single motion-reverser for simultaneously reversing the directional effects on the table 20 of both of said transmissions.

10. A shaper combining a body-casting; a ram; a unidirectional bull-gear; a cross-rail; a table; a transmission-system leading to said table; a bull-gear transmission; an 25 intermittent-motion transmission driven synchronously with said bull-gear and comprising a feed-stroke regulator located at the cross-rail; a fast-motion transmission driven at a rate proportional to the stroke frequency 30 of the ram; shift mechanism for causing either of said two transmissions to convey motion to said transmission system.

11. A shaper combining a table; a main body-casting; a propelling-transmission; a feed transmission comprising a motion converter at the cross-rail adapted to impart intermittent motion to said propelling transmission; a quick traverse transmission adapted to impart continuous motion to said propelling transmission; and a shift-mechanism 40 at the cross-rail for causing either said feed-transmission or said quick-traverse transmission to drive said table.

12. A shaper combining a body-casting; a ram; a unidirectional bull-gear; a cross-rail; a table; a transmission-system leading to said table; an intermittent-motion transmission and a continuous fast-motion transmission driven synchronously with said bull-gear; a clutch at the cross-rail for causing the fast-motion transmission to convey motion to said table transmission system; and motion-reversing means for reversing the directional effects on the table of both of 55 said transmissions.

13. A quick-traverse heavy-duty shaper for production manufacturing, combining a body-casting having a vertical front slide-way and a horizontal top-slide; a transverse cross-rail vertically adjustable; a table slideable on said cross rail transversely to said vertical slide-way and having a horizontal work-supporting surface; an auxiliary table-propelling transmission; a horizontal ram overhanging said table; a main-line transmission leading to said ram for periodically reciprocating it in said top-slide slowly to and rapidly from along a fixed path parallel with but above said work-supporting surface; a tool-head on the over-hanging extremity of said ram and adjustable in a plane perpendicular to the path of said ram to determine the depth of cut of its tool; a fast-running branch-line transmission and an intermittent motion transmission, each 70 deriving motion from the portion of said main-line transmission determining the stroke frequency of the ram; shift mechanism combined with last-mentioned transmissions for enabling either at option to drive said auxiliary transmission for feeding said table step-by-step along said cross-rail transversely to said path to project successive horizontal strips of the work thereon into the horizontal path of the tool carried by said ram, or for quickly traversing said table along said cross-rail transversely to said path; and a manual control for said shift mechanism for causing either the intermittent or the quick-traverse means to propel said table by power.

14. A shaper combining a body-casting; a ram; a unidirectional bull-gear; a cross-rail; a table; a transmission-system leading to said table and comprising a single unidirectional shaft from the side of said body-casting adjacent said bull gear to said cross-rail; a bull-gear transmission; an intermittent-motion transmission driven by said unidirectional shaft synchronously with said bull-gear and comprising a feed-stroke regulator located adjacent said cross-rail; a fast-motion transmission; and a single motion-reverser located at the cross-rail for simultaneously reversing the directional effects on the table of both of said transmissions.

In witness whereof, I have hereunto subscribed my name.

WILLIAM F. ZIMMERMANN.
